UNITED STATES PATENT OFFICE.

WILLIAM D. WOOD, OF SEATTLE, WASHINGTON.

PHOTOGRAPHIC-PRINTING MACHINE.

1,384,372.

Specification of Letters Patent. Patented July 12, 1921.

Application filed August 26, 1920. Serial No. 406,084.

To all whom it may concern:

Be it known that I, WILLIAM D. Wood, a citizen of the United States, and residing at Seattle, in the county of King and State 5 of Washington, have invented certain new and useful Improvements in Photographic-Printing Machines, of which the following is a specification.

This invention relates to improvements in 10 photographic printing machines of that type wherein the negative is supported upon a transparent bed plate, and the printing paper forced onto the negative by the manual operation of a pressure pad, the illumination or light necessary for exposure being 15 automatically maintained while the pressure pad is in operative relation to the bed.

The main object of the present invention is to provide a superior printing pad, with 20 oscillating movement and an automatic numbering device and a perforated scale in adjustable masks.

In the drawings:

Figure 1 is a plan view of the improved 25 machine.

Fig. 2 is a side elevation of the same.

Fig. 3 is a longitudinal section with the pressure pad in operative position.

Fig. 4 is a broken sectional view illustrating 30 more particularly the numbering machine for the prints.

Fig. 5 is a sectional detail illustrating the numbering machine for indicating the number of operations of the pressure pad.

Fig. 6 is a diagrammatic view illustrating 35 more particularly the lighting system.

Fig. 7 is a diagrammatic view illustrative of the various circuits.

The improved machine comprises a hollow 40 box-like base 1, the top of which provides a bed 2 for the printing operation. A frame including side bars 3 and a forward or handle bar 4 is pivotally mounted at 5 in brackets 6 secured to the bed plate near one 45 edge thereof. An oscillating pressure pad 7 is supported in the frame, having pin and slot connection 8 with the side bars 3, in order that the operative face of the pressure pad may adjust itself to any irregularities 50 of the bed, negative or paper. The lower or operative face of the pressure pad has a felt or other suitable covering 9, and one edge of such pressure pad is preferably provided with a paper holding clip 10 having an en- 55 gaging lip 11 to underlie the operative face of the pad, and a corresponding lip 12

guided by headed pins 13 projecting from the upper surface of the pad and held at its upper limit of movement by a spring 14. Obviously by pressure on the lip 12 the printing paper indicated at 15 may have its edge inserted between the lip 11 and the surface 9 of the pressure pad.

The rear edge of the pressure pad is formed with an opening 16, in which on a 65 spring controlled pin 17 is mounted a numbering stamp 18. This stamp is capable of rotation on the pin. The frame of the numbering stamp has a projection 19, adapted, as the pressure pad and carrying frame 70 thereof is elevated to engage a roller 20 carried by one end of the standard 21 supported by an upright 24 secured to the base 1. As the pressure pad and the carrying frame is elevated, the numbering machine will be 75 turned on its pivot so that the printing face thereof will engage an inking roller 25 secured on the upright 24.

The bed plate 2 of the base is provided with an aperture 28 adapted to be closed by 80 transparent material 29. The bed is provided with masks 30 defining the outline of the opening 28, two of said mask guides having elongated apertures 31. Cross masks 32 are disposed in right-angular relation over 85 the transparent material 29, one edge of each of said strips having a thumb screw 33 extending through one of the apertures 31. The masks 32 may by relative adjustment, for instance through gage openings 34 90 formed in the edges of such masks, define a printing opening as 35. The size of said opening may be thus adjusted in accordance with the desired border or other detail of the print to be made. A negative holding 95 clip 36 is secured upon the bed plate to secure the negative in position, this clip being manually raised when desired to insert the negative through a lever 37 pivotally secured at 38 on the underside of the bed plate and having an upstanding projection 39 to engage beneath the clip 36 at one end, the other end of the lever having a projection 40 extending through the bed plate and terminating in a button 41.

The light means for exposure is provided 100 by a lamp 42 mounted within the base 1, and having a circuit 43 from a source of energy 44, which circuit is broken at 45 in spaced contacts which extend above the bed plate 2. 110 These contacts are bridged to close the circuit by member 46 carried upon a rod 47 hav-

ing a spring mounting at one end as at 48 in a supporting bracket 49 rising from the base 1. The other end of the rod 47 extends beneath a roller 50 on the carrying frame, so 5 that as said frame is depressed to move the pressure pad to operative position, the circuit will be closed to light the lamp 42.

To provide for readily determining the last number on the numbering machine 18, 10 there is arranged on the bed plate a mirror 51 supported in a suitable upright, in which mirror the last number on the numbering machine is reflected when the carrying frame and the pressure pad is in elevated position. 15 This enables the operator to adjust such machine when changing prints.

What I claim is:

In a photographic printing machine, a

base having a source of light, an opening therein covered by transparent material to 20 receive the negative, a carrying frame pivotally mounted on the base, a pressure pad carried by and having a limited free movement with respect to the frame, a spring rod supported on the machine and having a 25 sliding connection with the carrying frame, a light circuit having spaced contacts arranged in the path of movement of said rod in the operation of the carrying frame, whereby said rod is adapted to close and open said circuit as the carrying frame is moved to an operative or inoperative position.

In testimony whereof I affix my signature.

WILLIAM D. WOOD.
